Patented Aug. 23, 1921.

25 Inventor
Layton M. Musselman,
By his Attorneys

UNITED STATES PATENT OFFICE.

LAYTON M. MUSSelman, OF JERSEY CITY, NEW JERSEY.

HORSESHOE.

1,388,477.

Specification of Letters Patent. Patented Aug. 23, 1921.

Application filed June 15, 1920. Serial No. 389,140.

To all whom it may concern:

Be it known that I, LAYTON M. MUSSelman, a citizen of the United States, and residing at Jersey City, in the county of Hudson and State of New Jersey, have invented certain new and useful Improvements in Horseshoes, of which the following is a specification, such as will enable those skilled in the art to which it appertains to make and use the same.

This invention relates to horseshoes and the object thereof is to provide a shoe of this class with means for preventing a horse from slipping on icy or frozen streets or roads; a further object being to provide a horseshoe with main toe and heel calks and supplemental toe and heel calks detachably connected with the main toe and heel calks, the construction and arrangement being such that the supplemental toe and heel calks may be detached and new ones substituted whenever desirable; a still further object being to provide a horseshoe with supplemental toe and heel calks which are made of angular plates or angle-iron, L-shaped in cross-section and provided with means whereby they may be securely locked in position against movement in any direction and especially against movement forwardly and backwardly and transversely; and with these and other objects in view the invention consists in a device or devices of the class specified, constructed as hereinafter described and claimed.

The invention is fully disclosed in the following specification, of which the accompanying drawing forms a part, in which the separate parts of my improvement are designated by suitable reference characters in each of the views, and in which:

Figure 1 is a bottom plan view of a horseshoe provided with my improved toe and heel calk constructions, part of said toe and heel calk constructions being in section;

Fig. 2, a section on the line 2-2 of Fig. 1;

Fig. 3, a view looking in the direction of the arrow 3 of Fig. 2;

Fig. 4, a view looking in the direction of the arrow 4 of Fig. 1;

Fig. 5, a section on the line 5-5 of Fig. 1; and

Fig. 6, a perspective view of one of the detachable heel calk members which I employ.

In the drawing forming part of this specification, I have shown at 1 a horseshoe which is preferably stamped or otherwise formed from a steel plate, and said horseshoe is provided with a main transverse toe calk member 2 which is formed integrally therewith and with an upwardly directed toe piece 3, which is cut from the material of the main transverse calk member 2 thus forming an aperture 4 in said calk member.

I also provide a supplemental toe calk member 5 which is fashioned from sheet steel and L-shaped in cross-section and composed of a horizontal plate member 6 and a vertically arranged plate member 7 which abuts against the main transverse toe calk member 2, and the body of the shoe with the transverse main calk member 2 forms an angular or L-shaped bed or support for the supplemental calk member 5.

The parts 6 and 7 of the supplemental toe calk member 5 are provided with bolt holes 8 and this calk member is locked directly to the main transverse toe calk member 2 by a U-shaped bolt 9, the arms 10 of which are passed through the parts 2 and 7 and provided with nuts 11, which are locked against rotation by a nutlock plate 12 placed against a face of the main transverse front toe calk member 2, and the ends of which are bent up over the outer sides of said nuts as clearly shown at 13. With this construction, as will be seen, the arms 10 form bolts which are integral with the cross-head member 9 and said bolts cannot rotate independently, and this also aids in locking the nuts 11 in position on said bolts.

The parts 6 and 7 of the supplemental toe calk member 5 are also provided with upwardly and outwardly directed transverse lugs 14 and 15 respectively, and the shoe 1 is provided with a transverse aperture 16 to receive the lug 14, and the lug 15 passes into the aperture 4 in the main transverse toe calk member 2, as clearly shown in Fig. 2, and the parts 6 and 7 of the toe calk member 5 are also provided in their inner ends, in the construction shown, with transverse recesses 17 and 18 respectively, which are formed by producing the lugs 14 and 15 which are stamped from the parts 6 and 7. The parts 6 and 7 of the supplemental toe calk member 5 are deeper or wider in transverse section than the main transverse toe member 2, and

said parts 6 and 7 are of the same transverse width or dimensions; and with this construction, as will be understood, the position of the supplemental toe calk member 5 may be reversed when one of said parts 6 or 7 has become worn.

The side portions 19 of the shoe are provided with main heel calk members 20 which are also L-shaped in form, the longer arms 10 or end portions 21 thereof extending longitudinally of the shoe and the shorter arms or end portions 22 thereof inwardly and transversely of the shoe, and the sides of the shoe are provided with recesses or apertures 23; and the transverse parts 22 of the calk members 20 are provided with fingers 24 which pass through said recesses or apertures and are riveted, welded, or otherwise secured therein.

20 I also provide supplemental and detachable heel calk members 25 which are L-shaped in form, the longer arms 26 thereof extending longitudinally of the shoe, and the shorter arms 27 thereof inwardly and transversely of the shoe; and these supplemental heel calk members 25 are adapted to fit in the angles of the main heel calk members 20 and the transverse parts 27 thereof are provided with hook members 28 which pass through, or are adapted to be passed through, corresponding transverse apertures 29 in the transverse parts 22 of the main heel calk members 20, and the body of the shoe with the main heel calk members 20 forms three-sided beds or supports for the supplemental heel calk members 25.

The longer parts 21 and 26 of the heel calk members are also provided with bolt holes 30, 40 and I also provide U-shaped lock bolts 31 which are passed inwardly through the bolt holes 30, as clearly shown in Fig. 1, and the inner arms of the lock bolts 31 or those nearest the transverse center of the shoe are provided with nuts 32; and placed on the inner sides of the parts 26 of the supplemental heel calk members 25 are nut lock plates 33 through which both arms of the lock bolts 31 pass. The inner ends of the lock plates 33 are bent up over the nuts 32 as shown at 34 to prevent said nuts from rotating.

The side portions of the shoe are provided with backwardly directed extensions 35 which are designed to protect the parts 28 of the supplemental heel calk members 25; and with the construction above described, it will be seen that the said supplemental heel calk members 25 when once secured in position are immovable in any direction, and these 55 heel calk members or the positions thereof cannot be reversed.

The vertical or transverse dimensions of the supplemental heel calk members 25 are also greater than the corresponding dimen-

sions of the main heel calk members, and it 65 is these parts of the supplemental heel calk members that come in contact with the ground when the shoe is in use and prevent the horse from slipping or sliding on frozen or icy streets or roads, as is also the case 70 with the supplemental toe calk member.

The main idea of the invention herein described is the provision of angle-iron supplemental toe and heel calk members which may be securely locked in connection with 75 the main heel and toe calk members so as to prevent lateral, vertical, or forward and backward movement thereof, and which are specifically formed, as herein described, and also provided with efficient means for locking them in position on to the shoe, but which may be detached for the purpose of substituting new supplemental calk members whenever necessary or desirable; and while I have shown specific forms of construction for carrying my invention into effect, my invention is not limited to these forms, and changes therein and modifications thereof may be made, within the scope 80 of the appended claims, without departing 90 from the spirit of my invention or sacrificing its advantages.

It will also be seen from the foregoing description that the toe portion of the shoe and the main transverse toe calk member 2 95 integrally connected therewith form a bed or support which is L-shaped in cross-section and this, of course, facilitates the placing of the supplemental toe calk member in position and securing it therein; and the above 100 is also true of the heel calk members except that the main heel calk members taken in connection with the side portions of the shoe form double L-shaped or angular-shaped supports for the supplemental heel 105 calk members and also facilitate the use of supplemental heel calk members of the form shown and described and the securing thereof in position.

As hereinbefore stated the shoe 1 and the 110 main calk members are preferably stamped from sheet steel and this enables me to produce a shoe which will possess all the necessary strength and durability, while at the same time being of minimum weight; and the supplemental toe and heel calk members are also stamped or otherwise formed from sheet steel, which gives them great strength 115 and durability and the bearing edges or surfaces thereof which come in contact with the street or road over which a horse is passing are comparatively thin and do not need sharpening to prevent slipping.

Having fully described my invention, what I claim as new and desire to secure by 125 Letters Patent, is:—

1. A horseshoe provided with a main toe calk member and with L-shaped main heel

- 5 calk members, the longer arms of which extend longitudinally of the sides of the shoe and the shorter arms transversely thereof, and supplemental toe and heel calk members
 5 which are angular in form and fitted within the main toe and heel calk members and secured in position by **U**-shaped bolts.
2. A horseshoe provided with a main toe calk member and with **L**-shaped main heel
 10 calk members, the longer arms of which extend longitudinally of the sides of the shoe and the shorter arms transversely thereof, supplemental toe and heel calk members which are angular in form and fitted within
 15 the main toe and heel calk members and secured in position by **U**-shaped bolts, one of said **U**-shaped bolts being passed through a part of the supplemental toe calk member and through the main toe calk member and
 20 provided with locked nuts, and others of said bolts being passed through parts of the supplemental heel calk members and the main heel calk members and provided with locked nuts.
- 25 3. A horseshoe provided with a toe calk and with **L**-shaped main heel calks, the longer arms of which extend longitudinally of the sides of the shoe and the shorter arms transversely thereof, and supplemental heel
 30 calks set into the main heel calks, and similar thereto in form, and secured thereto and to the shoe by **U**-shaped bolts passed through the longer arms of the main and supplemental heel calks.
- 35 4. A horseshoe provided with a toe calk and with **L**-shaped main heel calks, the longer arms of which extend longitudinally of the sides of the shoe and the shorter arms transversely thereof, and supplemental heel
 40 calks set into the main heel calks, and similar thereto in form, and secured thereto and to the shoe by **U**-shaped bolts passed through

the longer arms of the main and supplemental heel calks, and provided with locked nuts.

5. A horseshoe provided with main heel
 45 calks which are **L**-shaped in form, the longer arms of said calks extending longitudinally of the sides of the shoe and the shorter arms transversely thereof, and supplemental heel calks similar in form to the main heel calks,
 50 said supplemental heel calks being provided with lock devices adapted to be passed through parts of the main heel calks, and said supplemental heel calks being also adapted to be secured to the main heel calks
 55 by **U**-shaped bolts.

6. A horseshoe provided with main heel calks which are **L**-shaped in form, the longer arms of said calks extending longitudinally of the sides of the shoe and the shorter arms
 60 transversely thereof, and supplemental heel calks similar in form to the main heel calks, said supplemental heel calks being provided with lock devices adapted to be passed through parts of the main heel calks, and
 65 said supplemental heel calks being also adapted to be secured to the main heel calks by **U**-shaped bolts provided with nuts and means for locking said nuts in position.

7. A horseshoe provided with a main
 70 transverse toe calk and with main heel calks which are angular in form, supplemental toe and heel calks angular in form, and **U**-shaped bolts provided with lock nuts for securing said supplemental toe and heel
 75 calks to the main toe and heel calks.

In testimony that I claim the foregoing as my invention I have signed my name in presence of the subscribing witnesses this
 14th day of June, 1920.

LAYTON M. MUSSELMAN.
